UNITED STATES PATENT OFFICE.

JUNE B. RAND, OF LOS ANGELES, CALIFORNIA.

CAP.

1,268,614.

Specification of Letters Patent. Patented June 4, 1918.

Application filed July 7, 1917. Serial No. 179,162.

To all whom it may concern:

Be it known that I, JUNE B. RAND, a citizen of the United States, residing at Los Angeles, in the county of Los Angeles and 5 State of California, have invented new and useful Improvements in Caps, of which the following is a specification.

My invention relates more particularly to that type of cap commonly utilized by 10 women when engaged in household duties.

A prime object of my invention is to provide a novel form of house cap that is composed of a single piece of flat material that may be easily folded and detachably secured 15 together so as to form a cap of great utility and beauty.

A further object is to provide a novel form of cap that may be easily and conveniently laundered when soiled, and that has no attachment thereto that will render laundrying a difficult operation.

A still further object is to provide a cap construction which, when folded and secured into shape for use, will effectually protect 25 the wearer's hair when dusting, and at the same time permit the air to circulate freely therethrough.

I accomplish the above objects by means of the cap herein described and illustrated 30 in the accompanying drawing, in which:

Figure 1 is a perspective view of my cap, showing it in use on a person's head.

Fig. 3 is a side elevation of my cap.

Fig. 2 is a plan view of my cap in its un- 35 folded form.

Referring more specifically to Fig. 2 of the drawing, the cap preferably consists of a flat rectangular body 5, composed of two layers of "wash" material 6 and 7, stitched 40 together at the edges thereof. Secured to the rear edge 8 of the body 5 is a rear or tail portion 9, preferably formed of a single ply of material, so that when in place on a person's head it will readily conform to the 45 hair and fold gracefully without wrinkling. This rear portion 9 is secured to body 5 mid-way between said body's edges 10 and 11, as clearly shown in Fig. 2 of the drawing.

Formed in two of the inner oppositely 50 disposed corners and adjacent edges 8, 10 and 11 of the body portion 5 are button holes 12 and 13 angularly disposed with respect to said edges and engaged by buttons 14 and 15. When the cap is folded for use, 55 button 14 engages button hole 12, and button 15 engages button hole 13.

The transversely disposed edge of the rear portion 9 is preferably cut angularly, as shown in Fig. 2, so that when the cap is folded and in place on a person's head, said 60 edge will readily conform to the wearer's neck and present an attractive appearance.

The front edge of body portion 5 is adapted to be folded on itself and preferably at about the distance from the outer edge, 65 as indicated by dotted line 16 in Fig. 2.

To further add to the beauty of design, I have secured to the edges of the body portion and rear portions, an ornamental taping 17, here shown as of serpentine form, although other forms of ornamentation may be employed. This taping 17 is secured to the underside of rear portion 9 and the rear edge 8 of body portion 5 and extends upwardly along end edges 10 and 11 of body 70 portion 5 to the point of fold, indicated by the dotted line 16. The tape is then brought up from the under face of layer 7 and continued along edges 10 and 11 and the horizontally disposed front edge of body 5, and 75 secured to the top face of body portion 6 at the edge thereof. This method of securing the tape to the edges of the cap is to secure a uniform edge when the cap is folded, as clearly shown in Figs. 1 and 2 of the 80 drawings.

The rear or tail portion 9 is of a sufficient length so that when the ends are secured to the body portion 5, there will be sufficient room to accommodate a woman's hair, which 85 is generally massed on the rear of the head. The body portion, when folded, extends across the front of the wearer's head, and the points of attachments being approximately at the wearer's ears, the extreme end 95 portion of the tail portion extending forwardly when the cap is folded and secured so as to closely fit the back of the wearer's neck, as clearly shown in Fig. 1 of the drawing.

If desired, the body 6 and rear portion 9 100 may be formed out of a single piece of material, formed by dies so that a large number would be cut at a single operation.

From the foregoing description, it will be 105 observed that I have provided a one-piece cap that may be easily and readily formed into shape, and which is of great utility and beauty.

What I claim is:

A cap construction, comprising two substantially rectangular flat portions formed

100

2
from a fabric, said portions being secured together at substantially right angles to each other to form a T shaped figure, a button secured in each of the corners of the free end 5 of one of said portions adapted to engage button holes in the corners formed by the rear and side edges of the other of said portions, whereby when the two portions are

secured together ventilating openings will be formed on either side of the cap construction. 10

In witness that I claim the foregoing I have hereunto subscribed my name this 13th day of June, 1917.

JUNE B. RAND.
